UNITED STATES PATENT OFFICE.

OSCAR L. EVANS, OF EXCELSIOR, MINNESOTA.

ERASER-CLEANING MACHINE.

Application filed August 4, 1921. Serial No. 489,377.

To all whom it may concern:

Be it known that I, OSCAR L. EVANS, a citizen of the United States, residing at Excelsior, in the county of Hennepin and State 5 of Minnesota, have invented certain new and useful Improvements in Eraser-Cleaning Machines; and I do hereby declare the following to be a full, clear, and exact description of the invention, such as will enable others skilled in the art to which it 10 pertains to make and use the same.

My invention has for its object to provide an eraser cleaning machine of high capacity and efficiency, and which will remove 15 the chalk dust from the erasers and discharge the same outside of the building in which the machine is used or at any other suitable place.

Generally stated, the invention consists 20 of the novel devices and combinations of devices, hereinafter described and defined in the claims.

Machines of this character will be found especially serviceable and desirable for use 25 in large grade schools and high schools where a very large number of erasers should be cleaned during a very short space of time.

In the accompanying drawings, which 30 illustrate the invention, like characters indicate like parts throughout the several views.

Referring to the drawings:—

Fig. 1 is a plan view of the machine;

Fig. 2 is a side elevation thereof;

Fig. 3 is a vertical section taken on the 35 line 3—3 of Fig. 1, some parts being broken away; and

Fig. 4 is a transverse vertical section taken on the line 4—4 of Fig. 1, some parts being broken away.

As preferably constructed, the machine is 40 provided with a sheet metal housing 5 having a depending portion 6 and a discharge spout 7, at or near one end. This discharge spout 7 will be extended to the exterior of

45 the building in which the machine is installed or to any other suitable place where the discharge of the chalk dust will not be objectionable. The depending portion 6, in one side, is provided with a door 8 and the 50 main body of the housing 5 is provided with a displaceable cover plate 9 shown as slidably mounted.

The housing described and certain other 55 parts, presently to be described, are shown as supported by a rectangular framework 10, of wood or other suitable material.

Rigidly supported by the frame-work 10 and extended along the lower portion of, and into the housing 5, is a feed table 11, the receiving end of which is outside of said 60 housing.

In this machine, a blast of air is blown into the housing 5 from the fan, made up of a casing 12 and co-operating fan-head 13, which latter is carried by a shaft 14 journaled in suitable bearings on the frame 10 and provided with a pulley 15, over which a power-driven belt 16 is arranged to run. The belt 16 may be driven from an electric 70 motor or any other suitable source of power.

The fan-casing 12 has an air discharging spout 17 that opens into the front end of the housing 5 at a suitable point above the table 11; and between said spout and table, below said table, said housing is left open for the feed passage of the erasers and feed belt. The said feed belt is in the form of endless parallel strips of leather, or other flexible material and is provided with transversely extended longitudinally spaced 80 slats 19 secured thereto. The erasers are indicated by the letter Y. Said feed belt runs over rollers 20 and 21 journaled in the upper laterally spaced beams 10^a of the frame 10. The roller 21 is an idle roller, but the roller 20 is a driving roller, and its shaft 20^a projects at one end, and is provided with a pulley 22. Said feed belt or apron 18 runs over and beneath the table 11 and its operative upper portion moves frictionally upon said table and is supported thereby.

Overlying the inner portion of the table and feed belt and suitably spaced above the same, is a cylindrical brush 23, the shaft 24 of which is journaled in suitable bearings on the frame beams 10^a, and one projecting end is provided with a pulley 25.

The fan shaft 14, at its rear end, is provided with a beveled pinion 26 that meshes with a bevel gear 27 on a transverse shaft 28 journaled in suitable bearings on the main frame 10. At one projecting end, the shaft 28 is provided with pulleys 29 and 30, and, at the other end, it is provided with a crank 31. The pulley 30 carries a crank pin 32 that serves as a companion crank to said crank 31.

Working within the housing 5 between the front or receiving end thereof and the 110 rotary brush 23 is a beater plate or board 33, preferably grooved on the under side and

provided with upwardly projecting studs 34 that extend through oscillatory arms 35, the downturned front ends of which, as shown, are pivoted in transverse rods 36 just above the line of movement of the upper portions of the erasers Y. Coiled springs 37 surround the studs 34 and are compressed between the beater board 33 and the arms 35. Collars 38, fixed on the studs 34, limit the downward movement of the beater board 33 from the arms 35.

For oscillating the beater board 33, oscillatory movement is directly given to the arms 35, through laterally spaced pitmans 39, or connecting rods 39, the upper ends of which are pivoted to the ends of a cross-bar 40 which connects the arms 35. The lower ends of the pitmans 39 are pivotally connected, one to the crank 31 and the other to the crank pin 32 of the pulley 30. The ends of the cross-bar 40 work through openings in sides of the casing and are attached to flexible sheets 40^a that keep said openings closed.

25 A belt 41 runs over the aligned pulleys 29 and 25 to impart rotary motion to the cylindrical brush 23; and a crossed belt 42 runs over the aligned pulleys 30 and 22 to transmit motion to the roller 20 and, hence,
30 to the feed belt.

For holding the erasers down upon the feed belt and to prevent jumping actions of the erasers while they are being beaten, I provide a plurality of longitudinally extended, laterally spaced, flexible cables 43. These cables 43 may be hemp cords, wires, small wire cables or the like, and at their front ends, they are shown as attached to the transverse rod 36, while at their rear ends, they are anchored to a transverse tension rod 44, the ends of which latter project through slots in the sides of the housing 5 and are connected to coiled springs 45 anchored to said housing. The springs 45 keep all of the cables or cords stretched taut and positioned just above the upturned felt surfaces of the erasers.

Operation.

50 The operation of this improved machine is substantially as follows: The erasers to be cleaned are spaced side by side in rows between the slats 19 of the feed belt, with their felt faces turned upward. In this 55 way, a very large number of erasers may be kept constantly on the feed belt and subject to the beating action of the beater board or plate 33. When the machine is in 60 operation, the beater board 33 will be rapidly vibrated or oscillated upward and downward, and under each downward movement, it will strike and beat the chalk laden felt faces of the erasers, thereby loosening up and beating out the chalk dust.

65 The erasers will be quite well cleaned

before they reach the rotary brush 23, but by the latter, the remaining loose dust will be brushed out from the felt faces of the erasers. This cleaning action is, of course, greatly accelerated by the action of the air blast which is blown through the housing, and constantly carries off the loosened chalk dust without giving the same a chance to settle, after having been loosened up. In addition to its beating action, the beater board 33, under both downward and upward movements tends to carry and blow the chalk dust out of the erasers. 70 75

It is further important to note, first, that the air blast is blown through the housing in the same direction in which the erasers are fed thereto; and second, that the cylindrical brush 23 is rotated in a direction to discharge the dust from the erasers in the same direction in which the erasers are being fed through the housing by the feed belt. Hence, both the action of the air blast and of the rotary brush serve to increase the rapidity with which the loosened chalk dust will be delivered through the discharge spout 7. 80 85 90

It should be further noted that the beater board 33 is so flexibly or yieldingly connected to the supporting arms 35 that it will adapt itself universally to varying or irregular surfaces produced by the upturned felt faces of the erasers engaged thereby. Moreover, the said beater board 33, when stopped against the erasers, does not prevent further movements with the arms 35. Hence, said arms may be arranged for greater oscillatory movement than that of the beater board, and the beater board will be given such self-adjusting action that it will adapt itself to the beating of erasers of different thicknesses without requiring re-adjustment of the machine.

The erasers to be cleaned are placed on that portion of the feed belt that is outside of the casing, and the cleaned erasers will be dropped from the feed belt into the depending portion 6 of the housing and may be removed therefrom, when the door 8 is opened. Inasmuch as the blast of air is directly through the discharge spout 7, there will be no air pressure above atmospheric pressure in the depending portion 6 of the casing, and consequently, the door 8 may be opened at any time for the removal of the cleaned erasers. 110 115 120

What I claim is:—

1. In a machine of the kind described, a housing having an air intake at one end and an air outlet at its other end, of a power-driven fan having a discharge spout 125 connected to the air intake of said housing, a power-driven horizontally disposed feed belt operative to feed erasers into said housing in a direction from said air intake toward said air outlet, a table over which the 130

upper portion of said feed belt moves, a beater board working above said feed belt, pivoted arms yieldingly connected to and supporting said beater board, and power-
5 driven crank devices connected to said arms for oscillating the same.

2. The construction defined in claim 1 in further combination with retaining cables laterally spaced and supported above said
10 belt and below said beater board.

3. In a machine of the kind described, the combination with a housing having an air intake at one end and an air outlet at the other end, of a deck extending under the
15 air intake and terminating short of the air outlet, a feed device arranged to feed erasers over the deck; a fan having a discharge spout at the air intake, and a beater working above the deck, said housing having a
20 discharge opening for the erasers below the inner end of the deck.

4. In a machine of the kind described, the combination with a housing, a deck, means for feeding erasers over the deck, a
25 beater working above the deck, pivoted arms yieldingly connected to and supporting the beater, means connected to the arms for oscillating the same, and means for forcing a blast of air through the housing.

5. In a machine of the kind described, the combination with a housing, of a deck, 30 means for feeding erasers over the deck, a beater working above said means and being in the form of a board having a grooved under surface, means for holding the erasers on the deck during the action of the beater thereon, and means for forcing a blast of air through the housing.

6. The structure defined in claim 5 in which said means for holding the erasers on the deck is in the form of flexible cables. 40

7. In a machine of the kind described, the combination with a housing, of a deck, means for feeding erasers over the deck, a beater working above said means, yieldingly held flexible cables for holding the erasers 45 on the deck during the action of the beater thereon, and means for forcing a blast of air through the housing.

8. The structure defined in claim 7 in further combination with a brush operative on the erasers between said cables and inner end of the deck. 50

In testimony whereof I affix my signature.

OSCAR L. EVANS.
